UNITED STATES PATENT OFFICE.

DAVID FROELICH, OF BROOKLYN, NEW YORK.

AWNNG-ROLLER CONSTRUCTION.

Application filed May 14, 1927. Serial No. 191,503.

This invention relates to improvements in an awning roller construction.

The primary object of the invention is to provide a positive means of fixing the awning roller to the drive spindle so that the roller will turn therewith during the winding and unwinding of the awning about the same.

Another object of the invention resides in an awning roller construction in which a recess is provided in one end of a roller to receive the bushing of a cap fixed to the end of a roller and through which bushing a spindle extends while a key passes transversely through the roller, bushing and spindle to keep the parts together to prevent any accidental turning of the same relative to each other upon rotation of the spindle.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a perspective view of my improved awning roller and its supporting means.

Figure 2 is a top plan view of the same.

Figure 3 is a horizontal sectional view on the line 3—3 of Figure 1.

Figure 4 is a detail perspective view of the supporting bracket.

Referring more particularly to the drawing, the reference numeral 10 designates my improved awning roller which comprises a solid wood body 11 having a flange cap 12 on each end thereof. The diameter of the cap is greater than the diameter of the body to permit of an outer tubular casing 13 to fit over the body and beneath the flange of the cap. A recess 14 is provided in the end of the body for receiving a bushing or sleeve 15 which extends inwardly from the cap and receives the inner end of a spindle or stub shaft 16. The inner face of the cap is provided with brads 17 at the joinder of the bushing therewith and which brads are embedded in the outer end of the body to maintain the cap in position thereon. After the cap has been applied to the end of the body, nails 18 are passed through openings in the cap and are driven into the body to prevent rotation of the cap with respect thereto. After the shaft has been inserted into the bushing, a nail or key 20 is driven transverse-

ly through the body and extends through the aligned openings provided in the bushing and shaft 16.

The outer end of the shaft 16 is journalled in a two-part housing 21 and extends slightly beyond the housing for a purpose to be presently explained. A worm gear 22 is fixed to the shaft 16 and is concealed within the housing, which worm meshes with a gear 23 fixed to a vertical operating rod 24 which depends from the housing and by which an operator imparts a turning movement to the roller. The construction of the winding mechanism is old in the art but has been shown and described for illustrating the type of device with which my invention is associated.

For removably supporting the awning apparatus upon a supporting structure such as the front of a building or the like, I provide a pair of spaced brackets 25 and 25' for respectively supporting the opposite ends of the roller. The bracket 25' is provided with an outwardly extending arm 26 having a notch 27 therein for receiving the stub shaft 28 extending from the end of the roller opposite to the end from which the shaft 16 extends. The shaft 28 is keyed to the body of the roller in the same manner as that described for the shaft 16.

The bracket 25 comprises a flat piece of strap metal bent to provide an attaching part 29 having openings therein for the passage of screws or like fastening elements 30. An arm 31 extends at right angle to the part 28 and is provided with a notch 32 for receiving the projecting end of the shaft 16, and a notch 33 for the reception of either of a pair of T-shaped lugs 34 and 35 which extend from opposite sides of the housing 21. The particular lug used for engagement with the notch 33 is dependent upon the position at which the bracket is mounted on a supporting structure. If the structure is of sufficient width to allow the bracket to be mounted as shown in the drawing, then it is mounted thusly, but should the winding apparatus project beyond the supporting structure, then the bracket is mounted to cause the lug 34 to seat in the notch 33 and the notch 32 will then receive the shaft 16 intermediate the roller and the housing 21.

What is claimed as new is:—

1. An awning roller comprising a body portion having a recess in an end thereof, a cap fitting against the end of said body, a

bushing extending from said cap into said recess, a spindle fitting within said bushing and extending therefrom, and a key passing transversely through said body, bushing and

5 spindle for keying the roller to the spindle.

2. An awning roller comprising a body portion having a recess in an end thereof, a flange cap fitting over the end of said body, the flange being disposed in spaced relation

10 to said body, a bushing extending from said

cap into said recess, a tubular casing fitting over said body and having its ends disposed beneath the flange of said cap, a spindle extending into said bushing, and a key passing transversely through said body portion, 15 bushing and spindle for keying the roller thereto.

In testimony whereof I have affixed my signature.

DAVID FROEHLICH.
